[57] CLAIM

The ornamental design for a note card and bulletin board easel assembly for a computer monitor, as shown and described.

DESCRIPTION

FIG. 1 is a top, front, right side perspective view of a note card and bulletin board easel assembly for a computer monitor; the broken lines indicating a computer monitor are shown for illustrative purposes only;

FIG. 2 is an enlarged top front right side perspective view thereof;

FIG. 3 is a front elevational view thereof;

FIG. 4 is a rear elevational view thereof;

FIG. 5 is a right side elevational view thereof, the left side being a mirror image thereof;

FIG. 6 is a top plan view thereof;

FIG. 7 is a bottom plan view thereof;

FIG. 8 is a top, front, right side perspective view of a note card easel assembly for a computer monitor, showing a modified embodiment of my new design;

FIG. 9 is a front elevational view thereof;

FIG. 10 is a rear elevational view thereof;

FIG. 11 is a right side elevational view thereof, the left side being a mirror image thereof;

FIG. 12 is a top plan view thereof; and,

FIG. 13 is a bottom plan view thereof.
